EM 003148667 5/2016

Primary Examiner — Rhea Shields(74) *Attorney, Agent, or Firm* — Design IP(57) **CLAIM**

The ornamental design for a neonatal care device, as shown and described.

DESCRIPTION

FIG. 1 is an upper right front perspective view of a first embodiment of a neonatal care device showing our new design;

FIG. 2 is an upper left rear perspective view thereof;

FIG. 3 is a front view thereof;

FIG. 4 is a rear view thereof;

FIG. 5 is a right side view thereof;

FIG. 6 is a left side view thereof; and,

FIG. 7 is a top view thereof.

The broken lines in the figures show portions of the neonatal care device that form no part of the claimed design.
